APPARATUS FOR THE PNEUMATIC SEPARATION OF MATERIALS OF DIFFERENT SPECIFIC GRAVITIES AND SIZES.

Frank Frost Ridley, Rutland Park, Sheffield, England, assignor to Colliery Engineering Limited, Yorkshire, England, a British joint-stock company

Application June 1, 1936, Serial No. 82,998
In Great Britain June 5, 1935

6 Claims. (Cl. 209—44)

This invention comprises improvements in apparatus for the pneumatic separation of materials of different specific gravities and sizes, such as apparatus for the dry cleaning, purification or separation of shale and such like impurities from coal. It is particularly concerned with the separation of the finest sizes of materials, for example the range from $\frac{1}{8}$ " to zero. It is also of particular utility in carrying out the process of separating such materials according to Patent No. 1,843,405 issued to George Raw on February 2, 1932, which relates to the use of static pneumatic pressure to achieve stratification between materials of different densities, but without regard to the sizes of the particles. This latter process is of particular usefulness in the treatment of fines, because it eliminates pre-sizing, which is especially difficult and troublesome in the finer sizes. The separate pneumatic treatment of very fine sizes, as compared with the larger material such as up to 1" or 2", has presented difficulties mainly owing to the much slower rate of stratification and the greater sensitiveness of the bed of materials to the pneumatic conditions applied to it. The slower rate of stratification of fine materials makes it desirable to operate on a relatively thin bed of materials, and also to provide a considerable length of table over which the materials have to pass and thus a considerable period of treatment, in order to ensure efficient purification. However, the greater sensitiveness of the bed when working with thin beds of fine materials, for example beds from 1" to 2" thick, imposes conditions of delicacy requiring accurate control in order to maintain, during the full period of stratification, the proper condition of balance and fluidity which is necessary for stratification in the bed of materials. As a result, it is found that there are practical limits to the length and area of bed which can be separately maintained in the proper and uniform condition required for stratification. If it is attempted to work with too great an area, it is found that, owing to inevitable variations in character of the materials, one part of the bed may be liable to burst under the influence of the pneumatic pressure and destroy stratification which has already taken place. In dry cleaning tables, the stratification of the materials and the separation of the layers one from another usually proceed concurrently and, in many cases, certain quantities of the coal or other less dense material are discharged progressively as they become freed of the denser

material or impurities, while the latter, such as concentrated shale or stone, progresses to the end of the table. However, with fine materials, owing to the slower stratification, this does not provide the best opportunities of completely purifying the coal. It is better to arrange for the coal or the like to pass over as nearly as possible the whole length of the table before discharge, thus subjecting it to the cleaning influence for the maximum period.

In some dry coal cleaning tables, attempts have been made to secure the advantage of this long treatment by employing various means for extracting the stratified shales through the deck or table surface and allowing the coal to pass on to the end, but difficulties have usually been associated with these discharge means. In the first place, it has been found that the fluid condition of a bed of fine materials on a long table or deck causes it to assume different thicknesses. This disturbance of the conditions of the bed upsets the stratification so that it is difficult to obtain effective discharge of the shale. In the second place, if the lower stratum be discharged directly from a slot device disposed transversely of the table, a large area will be provided sufficient for the undesired discharge of coal with shale. In addition pneumatic pressure is liable to escape violently through the slot instead of going through the bed. If, in order to avoid these defects, the slot be connected with a shale chute having intermittently operated means for discharging shale, the bed is disturbed by the intermittent action of such means. Alternately if the escape of air is avoided by disposing the slot in an impervious part of the table the portion of the bed in the neighbourhood of the slot is unsupported by pneumatic pressure and the bed will not be maintained in the desired fluid condition. Finally, means for shaving off the lower stratum and discharging it through a slot are liable to disadvantages owing to the fact that the shale occupies only a relatively thin layer, and the irregular shape of the particles produces an ill-defined line of demarcation between the strata.

The principal object of the present invention is to provide an improved construction for the efficient separation of fine materials on a long table, while avoiding undesirable fluctuations in thickness of the bed and providing for the discharge of the bottom layer in such a manner as to prevent undue disturbance of the fluid conditions of the bed.

According to this invention a table or deck disposed over an air box is divided into a number of

stratifying ones by transverse slopes or steps, and discharge of the lower stratum of materials is effected in a restrained manner, so as not to disturb the fluid conditions of the bed, by sieves, in the table disposed at the forward end of the zones. The division of the table by the slopes enables zones of predetermined area to be provided for ensuring proper control of the stratification conditions and for avoiding irregularities in the bed. Thus the table is divided into a number of zones or areas of a size not too large for proper control of the conditions, and before any irregularity is able to occur the stratification in one zone is completed, a part of the shale is discharged and the bed is re-formed for further treatment in the next zone. The coal is thereby subjected to a prolonged treatment in the succeeding zones and the shale is discharged without disturbing the conditions in the bed. In the absence of the slopes, the fluidity of the bed would cause it to run away at some points and build up at others. The re-formation of the bed in succeeding zones avoids this disadvantage.

The sieves are adapted for an effective discharge of the shale while preserving the uniform fluid conditions. The pneumatic pressure is able to pass through such sieves at all times owing to the disposition of the table over a single air box. The sieves are suitably provided by narrow transverse portions having perforations considerably larger than those in the deck and slightly larger than the size of the largest particles treated. These sieves enable the shale to be discharged in a restrained manner without in any way disturbing the conditions of the bed, the effect being to allow the lower surface of the shale layer to be discharged, in contradistinction to the discharge of the whole of a lower layer as in the case of an uncontrolled slot discharge.

In order to enable the invention to be readily understood reference will be made to the accompanying drawings, illustrating by way of example, different constructions of apparatus for carrying the invention into effect, in which drawings:—

Figure 1 is a side elevation with parts in section of one construction of apparatus in which the table is provided with sieves for discharge of the shale.

Figure 2 is a plan of Figure 1, with the dust hooding over the table removed.

Figure 3 is a section, to an enlarged scale, on the line III—III, Figure 2.

Figure 4 is a section, to an enlarged scale, on the line IV—IV, Figure 2.

Figure 5 is a diagrammatic view of a modified construction.

Figure 6 is a plan view of the forward end of a modified construction of table, and

Figure 7 is a central longitudinal section of Figure 6.

Referring to Figures 1 to 4, the apparatus comprises a rectangular table *a* of trough form with a perforate deck *b*, and upstanding sides *c* to maintain a given thickness of bed. The deck is divided into a number of stratifying zones or cells A, B, C, arranged at different relative levels, each one being lower than the one preceding it. The forward end of one zone is connected with the rearward end of the next zone by an imperforate sloping portion *d*. At the forward end of each cell, just before each slope *d*, there is set transversely in the deck, a narrow sieve *e* in which there are relatively large perforations,

adapted for the discharge from the deck of the largest particles of stratified shale or the like.

The table *a* built on a chassis *f* is suspended by steel hangers *g* at the four corners and is connected to any suitable conventional vibrating mechanism to give a small throw at high periodicity. The table is slightly declined from the feed end *a*¹ to the discharge end *a*² to secure progression of the materials by gravitational flow. Other vibrating mechanisms can be applied as alternatives, and if they provide a component which causes forward progression of the materials, the forward declination of the table will naturally be decreased. Pneumatic pressure is supplied by a fan *h* through the duct *i* and pulsator *j* to the air box *k*. A flexible connection *k*¹ is provided between the table and the air box. Dust hooding *l* may be provided over the table, any suitable means being employed for separating or settling the dust. The manner of supplying the pneumatic pressure is described and shown in patents issued to George Raw: No. 1,730,947, dated October, 1929; No. 1,811,026, dated June 23, 1931; and No. 1,843,405, dated February 2, 1932.

In operation, the raw materials such as coal fed to the table at *a*¹ flows in the manner of a liquid, under the influence of vibration and pneumatic pressure, the shale or the like gradually stratifying at the bottom of the bed. At the end of the first zone A, a certain amount of stratified shale has collected at the bottom of the bed, and this riddles through the sieve *e*. The partially cleaned coal or the like flows down the imperforate slope *d* and is subjected to further stratifying action in the next zone B, further shale or stone being discharged through the sieve of this zone. The treatment proceeds similarly in the next zone.

By dividing the deck into several zones or compartments with imperforate slopes between them, the table is divided into a number of stratifying areas of a size predetermined so as not to be too large for proper control of the conditions, and before any irregularity is able to occur treatment in one zone is completed and the bed re-forms for further treatment in the next zone. There is thus a deliberate and controlled discontinuity between each stratifying zone. At the same time, the coal is subjected to the desired prolonged period of treatment, and the shale is discharged without in any way disturbing the conditions in the bed. The use of sieves for the discharge of shale or stone, enables a restrained discharge action to be obtained, only part of the layer of shale being passed through any particular sieve. Only a thin stratum of the lower layer is discharged through any particular sieve. A protective layer of shale may thus be provided between the coal and the discharged shale, so as to prevent mixing and loss of coal in the shale. The present invention provides a progressive discharge of shale the heaviest and most easily stratified passing through the first sieve *e* and progressively lighter shale passing through the remaining sieves. In order to ensure discharge of completely clean coal at the forward end of the table, some coal may be allowed to be discharged with the last vestiges of shale passing through the final sieve. The product passing through this particular sieve would be principally middlings and could be extracted from the air box *k* by independent discharge means and re-fed to the table for re-treatment with the raw material. Such a re-feeding will

usually provide sufficient margin to compensate for variations in the quantity of shale in the raw feed. If desired, however, a further adjustment may be provided by arranging for one or more of the sieves to be put out of action by plates having perforations of the same size as the perforations in the main deck. For example as shown in Figure 3 closure plates m may be fitted under the table a on hinges n so that the plate can be swung clear of the sieve e (as shown in dotted lines) by a lever device n^1 on the side of the table. The plates m can be swung upwards to obstruct the sieves when desired.

Instead of allowing the coal to be discharged directly from the stratifying zone C , while the middlings and remnant of coal are discharged through the sieve e , the particular arrangement illustrated may be adopted. In this arrangement provision is made for a sharper final separation between the last portion of stone extracted and the middlings which would otherwise pass into the air-box k with the stone. Thus over the imperforate slope d of the last zone C there may be disposed a skimmer or cutter o . This skimmer, which may be vertically adjustable, divides the strata of the bed, middlings passing underneath the skimmer being diverted by deflectors o^1 into a central channel p having a perforated bottom. Above the skimmer plate o are provided deflectors o^2 which divert the coal flowing over the plate into side channels p^1 disposed alongside the central middlings channel p . The bottoms of the coal channels p^1 are normally blank, but may be provided with perforations if desired to permit of the air passing through the material to assist its passage to the end of the table. When perforated a further cleaning may take place in these channels, which are then provided with discharge slots at their forward ends to discharge any last vestiges of impurities. Such material discharged through the slots would contain coal and would be passed into the middlings for re-treatment. The slots in this case would be beyond the end of the air box so that the material can be passed into the main middlings chute.

In the channel p the middlings are subjected to a further stratifying action. A second coal skimmer plate q is provided at the end of the channel, the deflectors q^1 diverting coal into the side channels p^1 while the middlings pass underneath the plate into a short zone r . The clean coal is discharged from the channels p^1 into chutes s . As shown in Figure 4 the zone r is extended a short distance beyond the end of the air box k to allow the middlings to discharge into a middlings chute r^1 beyond the clean coal. If the bed were too sluggish however a small extension such as a pipe and a small box, connected to the air box could be provided for supplying air pressure also to the forward portion of the zone r . A skimmer plate t is provided at the forward end of the zone r . Shale passes under this skimmer to a discharge outlet u , while the upper stratum of middlings passing over the skimmer is diverted laterally by deflectors t^1 . A flap device v directs the middlings either into the outlet r^1 so that they may be re-fed to the table, or into the outlet s for the clean coal. The two positions of the flap device, which is adjustable by a handle v^1 , are shown in dotted lines, Figures 1 and 4.

In order to maintain even thickness of bed in the zones, small dams w , Figure 4 may be fitted just forwardly of the sieves e and across the full

width of the deck for retaining the bed at given thickness. These dams are, as shown, only very short, as the thin beds have very little tendency to thin or break away as they pass over the slopes between the cells. The dams must not be too deep or they would tend to cause the bed to pile up and thicken and thereby destroy the regularity of the bed conditions. The dam may alternatively be in the form of a blade x , Figure 3, which also serves for maintaining separation of the layers after discharge of impurities through the sieve e . The blade is disposed horizontally above the sieve and is connected to a somewhat wider blade x^1 disposed above the slope d at approximately the same inclination. One or both of the blades x , x^1 may be adjustable for varying their inclinations. The horizontal blade x serves to dam the forward flow of materials and thereby maintain an even thickness of bed, while the inclined portion x^1 serves to preserve on the next zone the stratification obtained in the preceding zone, since it will be realized from Figure 3 that the denser materials flow under the blade and the less dense materials flow over it.

The shale discharged through the sieves e falls into the air box k , Figure 1, and may be extracted therefrom by any suitable means incorporating an air-sealed discharge. For example, the shale may be discharged into a small enclosed hopper y fitted with a balance valve y^1 at the bottom to retain a given level of material in the hopper. A screw conveyor z disposed along the bottom of the air box feeds the shale into the hopper.

According to the modified arrangement shown in Figure 5 the table comprises three stratifying zones, although four or more may be employed, each zone having a sieve discharge at its forward end. In this arrangement shale or the like discharged through the sieves 18 falls through the air box k^2 and is discharged from hoppers 19 formed in the bottom of the box beneath the sieves. Middlings fall from the final sieve 18 through the air box to a third hopper 19^1 . The hoppers are fitted with automatic discharge valves $19a$ under constant air-lock conditions, conveyors being disposed beneath the hoppers for carrying the material away. Clean coal flows over the forward end of the table 20 to discharge. Additional hoppers would be provided in accordance with the number and position of the bottom discharges provided in the deck.

According to the modified arrangement shown in Figures 6 and 7, the shale and middlings are separated at the end of the central trough or channel 21 by the adjustable skimmer or cutter 22 . The middlings pass over the skimmer to a chute 23 and the shale passes beneath to another chute 24 . The two chutes 23 , 24 are in line with the central channel 21 just beyond the air box.

In normal circumstances, the sides of the table are parallel and of constant width, but under some conditions it may be found desirable slightly to vary the widths of the cells. The purpose of this is to accommodate variations in the rate of flow of materials, which sometimes is liable to occur with fine material of the kind in question, and may be caused partly by the removal of shale. Variations in width, however, are only slight, and may be suitably provided for by fitting strips or distance pieces to the insides of the walls of any particular section. Such variations in the widths of the cells are not for the purpose of varying the thickness of the bed but for the purpose of maintaining it at uniform thickness when

a tendency to thinning might otherwise occur, due to an increased rate of flow at one portion.

It will be seen that the whole object is to make practically the whole length of table available for cleaning the coal, while at the same time extracting the shale progressively as it becomes stratified, and without in any way interfering with the conditions of stratification. The sieves do not cause any tendency for the air pressure to be violent at these points, because the discharge is restrained and the stratified shale lies in a heavy bed upon them and prevents any such free flow of air. Also, when working under the static pressure condition, the size of discharge slots or perforations has very little effect, because the quantity of air flowing is negligible.

The improved tables are of particular advantage in carrying out the static pressure process of separation already referred to. They may be operated singly or in multiple or pairs. Two or more tables may be arranged side by side on one frame or chassis and provided with a common air box or chamber or separate air chambers or each of several separating units may comprise multiple tables side by side, for example in the manner described in patent application Serial No. 643,258 now Patent No. 2,100,670, issued to George Raw on November 30, 1937. One fan may be used to serve several tables or to serve several units each comprising several tables, connection between the fan and the air boxes or chambers being by branched pipes or otherwise and the pulsators of the several tables being set so as to give sequential pulsations through the several air boxes or chambers, where necessary, to preserve uniform load on the fan, as in Patent No. 2,100,670 above noted. In the case of tables placed in multiple side by side on a single chassis, the invention provides the advantage that all the less-dense materials are discharged at the forward end of the chassis and no side discharges are necessary. This enables the two or more tables or decks to be built adjacently and close together and only a partition or a single side wall need be used to divide one deck from another. As large a table as desired, within mechanical limits, can thus be built without departing from the best size of individually operating deck. The size of the tables can be increased as desired in practice, without the usual difficulty experienced in experimental development, that different dimensions do not proportionately increase.

The invention has been found of particular advantage in the treatment of fine coal, particularly below $\frac{1}{8}$ " or $\frac{1}{16}$ " in size, which has always been found the most difficult material to treat on pneumatic dry cleaning tables.

I claim:

1. Apparatus for the separation of materials of different specific gravities by stratification of the materials due to pneumatic pressure, comprising an air box, a table having a pervious bottom disposed over said air box, a number of impervious slopes extending transversely of the table to provide a number of stratifying zones at different levels, sieves for the discharge of the lower stratified layer disposed in the pervious bottom at the forward end of each zone, and controllable means adjustable for shutting off discharge through said sieves.

2. Apparatus for the separation of materials of different specific gravities by stratification of the materials due to pneumatic pressure, comprising an air box a table having a pervious

bottom disposed over said air box, a number of impervious slopes extending transversely of the table to provide a number of stratifying zones at different levels, narrow sieves for the discharge of the lower stratified layer disposed in the pervious bottom at the forward end of each zone and having perforations larger than those in said bottom, closure plates having perforations approximating to the size of those in the bottom, and means for adjusting said plates for obstructing the discharge of materials through said sieves into the air box.

3. Apparatus in accordance with claim 2, comprising pivotally mounted closure plates and handles external of the air box for adjusting said plates.

4. Apparatus for the separation of materials of different specific gravities by stratification of the materials, comprising an air box, a table disposed over said air box and having a stratification zone with a flat pervious bottom, means for maintaining a bed of materials of substantially even thickness on said zone, means for subjecting the bed to the influence of static pneumatic pressure for maintaining the bed as a whole in equilibrium with said pressure to induce a state of fluidity in the bed with the minimum escape of air therethrough and a narrow discharge sieve disposed in the pervious bottom across the width of the table at the forward end of the stratifying zone, said sieve being in pneumatic communication with the air box and having perforations larger than those in the pervious bottom and at least as large as the largest particles of the lower stratified layer of materials for riddling the lower layer into the air box at the end of the stratifying zone while the less dense materials stratified by said pneumatic pressure occupy the upper layer, due to the maintenance of the fluid conditions above the said sieves during the discharge therethrough of material from the lower stratified layer.

5. Apparatus for the separation of materials of different specific gravities by stratification of the materials, comprising pneumatic chamber apparatus, a table having a pervious bottom disposed over said pneumatic chamber apparatus, impervious slopes disposed at intervals transversely of the table to divide it into a number of stratifying zones at successively lower levels the farther they are disposed away from the feed end of the table, means on said table for maintaining a bed of materials of substantially even thickness thereon, means for subjecting the bed to the influence of static pneumatic pressure for maintaining the bed as a whole in equilibrium with said pressure to induce a state of fluidity in the bed with the minimum escape of air therethrough and a narrow discharge sieve disposed in the pervious bottom across the width of the table at the forward end of each stratifying zone, said sieve being in pneumatic communication with said pneumatic chamber apparatus and having perforations larger than those in the pervious bottom and at least as large as the largest particles of the lower stratified layer for the riddling of the lower layer into the pneumatic chamber apparatus at the completion of the stratification in each zone while the less dense materials stratified by said pneumatic pressure occupy the upper layer, due to the maintenance of the fluid conditions above the said sieves during the discharge therethrough of material from the lower stratified layer.

6. Apparatus for the separation of materials

of different specific gravities by stratification of the materials due to pneumatic pressure, comprising an air box, a table having a pervious bottom disposed over said air box, impervious slopes disposed at intervals transversely of the table to divide it into a number of stratifying zones at successively lower levels away from the feed end of the table, means on said table for maintaining a bed of materials of substantially even thickness thereon, a narrow discharge sieve disposed in the pervious bottom across the width of the table at the forward end of each stratifying zone, said sieve continuously allowing the

application of pneumatic pressure to material over it and having perforations larger than those in the pervious bottom and at least as large as the largest particles of the lower stratified layer for the riddling of the lower layer into the air box at the completion of stratification in each zone, blades disposed over said sieves for damming the flow of materials over the table and blades disposed over the slopes at approximately the same inclination for preserving in the next zone the stratification obtained in the preceding zone. 5 10

FRANK FROST RIDLEY.
